US00D592244S

(12) **United States Design Patent**
Hammad

(10) **Patent No.:** **US D592,244 S**
(45) **Date of Patent:** ** *May 12, 2009

- (54) **COMMUNICATION DEVICE WITH DIFFERENT GEOMETRICAL ENDS**
- (75) Inventor: **Ayman Hammad**, Pleasanton, CA (US)
- (73) Assignee: **Visa U.S.A. Inc.**, San Francisco, CA (US)
- (*) Notice: This patent is subject to a terminal disclaimer.
- (**) Term: **14 Years**
- (21) Appl. No.: **29/319,063**
- (22) Filed: **Jun. 3, 2008**

(57) **CLAIM**

The ornamental design for a communication device with different geometrical ends, as shown and described.

DESCRIPTION

FIG. 1 is a perspective view of a first embodiment of the communication device showing my new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a front elevation view thereof;

FIG. 7 is a rear elevation view thereof;

FIG. 8 is a perspective view of a second embodiment of the design;

FIG. 9 is a top plan view thereof;

FIG. 10 is a left side elevation view thereof;

FIG. 11 is a right side elevation view thereof;

FIG. 12 is a bottom plan view thereof;

FIG. 13 is a front elevation view thereof; and,

FIG. 14 is a rear elevation view thereof.
